UNITED STATES PATENT OFFICE.

HAROLD W. SHONNARD, OF NEW YORK, N. Y., ASSIGNOR TO J. JONES & SON, OF SAME PLACE.

DISTRIBUTION-BOARD FOR ELECTRIC CURRENTS.

SPECIFICATION forming part of Letters Patent No. 592,889, dated November 2, 1897.

Application filed November 17, 1896. Serial No. 612,402. (No model.)

To all whom it may concern:

Be it known that I, HAROLD W. SHONNARD, a citizen of the United States, residing at New York, in the county and State of New York, 5 have invented a new and useful Improvement in Distribution-Boards for Electric Currents, of which the following is a specification.

My invention relates particularly to distribution-boards for electric-light currents. 10 Heretofore in these distribution-boards the straight main-circuit bars of the two, three, or more wire system were supported upon blocks in a raised position above the flat bars of the branch circuits and were alternately 15 connected to said branch-circuit bars at the points of support, the branch-circuit bars being in turn secured to the insulating slab foundation. This construction is somewhat complex, wasteful of time, and expensive; and 20 the object of my invention is to simplify the construction, lessen the cost, and reduce the number of parts.

In carrying out my invention I secure the main-circuit bars directly to and in proximity 25 with the insulating slab foundation and in a plane parallel with the same, and simultaneously connect one part of the branch-circuit bars to the insulating slab foundation by the same connecting devices. The other 30 parts of the branch-circuit bars are also directly connected to the insulating slab foundation.

Where the branch-circuit bars cross the main-circuit bars they are a continuous strip 35 of sheet metal without joints, that is arched and passed over above said main-circuit bars a sufficient height to prevent any short circuit or spark. With these devices I employ metal plates secured to the insulating slab 40 foundation and forming terminals for the respective wires of the branch circuits, and between these plates and the branch-circuit bars I prefer to employ safety-fuses, and may also employ pivoted swinging switches.

45 In the drawings, Figure 1 is a plan view representing my improvement applied to a three-wire-system distribution-board. Fig. 2 is a section of the same at the line x of Fig. 1. Fig. 3 is a plan view representing 50 my improvement as applied to a two-wire-system distribution-board, and Fig. 4 is a

plan of part of a three-wire-system distribution-board and showing two branch circuits and the three-wire branch bars from the three main bars of the system.

55

The insulating slab base, of slate or other suitable material, is shown at A, and throughout the drawings the main-circuit bars of the three-wire system are shown at $a b c$ and those of the two-wire system at $a' b'$.

60

In Figs. 1, 2, and 4 the branch-circuit bars are shown at d , e , and f .

The main-circuit bars $a b c$ and the branch-circuit bars $d e f$ are connected as shown and secured directly to and in proximity with the insulating slab foundation A by screws or screw-bolts 67. One of two ways may be employed to secure the main and branch circuit bars together and to the slab foundation—viz., the bars b and f may be perforated and the screw-bolts 6 pass down through said bars and slab foundation, with the nut in the recess of the slab, or the bars $d e$ may be perforated and the bars $a c$ be made with threaded holes, and screws 7 may pass upward through the slab foundation and bars $d e$ into the bars $a c$. I, however, prefer the screws 6.

65

The bars f are each a continuous strip of sheet metal arched, as shown, at each side of their central portion and pass above and over the bars $a c$ at a sufficient height to prevent short-circuiting or sparks. The respective outer ends of the branch-circuit bars $d e f$ are flattened and connected to the insulating slab foundation by screws 8, that preferably 70 extend from the back through holes in said foundation and through said ends and nuts thereon clamp one end of the safety-fuses $k l$ to said bar ends and bind the parts in place.

75

The terminal plates m are secured to the slab foundation A by screws 9, which preferably 80 extend from the back through holes in said foundation and said plates, and also clamp and hold the other ends of the safety-fuses $k l$, and the short screws 10, with heads 85 countersunk in the foundation, pass through the plates m , and these screws 10 secure the wires 2 3 and 4 5 of the branch light-circuits.

90

I have shown and sometimes use the auxiliary terminal plates m' and pivoted swinging 95 switches $n o$, of usual character, connected thereto and adapted to complete the electric 100

circuit with the branch-circuit plates, as shown in Fig. 1. These plates m' are secured to the slab foundation in a manner similar to that shown in connection with the plates m .

5 The respective ends of the main-circuit bars $a b c$ and $a' b'$ are provided with connectors l to receive the wires of the main circuit in making electric connection with said bars.

In Fig. 3 the branch-circuit bars $h i$ of the two-wire system are each a continuous strip of sheet metal without joints, and are alike, but in reversed position—that is, the bars h contact with the bar b' and extend up and over the bar a' at their arched portion, and the bars i contact with the bar a' and by their arched form extend over above the bar b' , screws or screw-bolts, as hereinbefore described, securing the bars i and bar a' and the bars h and bar h' to the insulating slab foundation A, the other parts being the same as hereinbefore described under similar letters of reference.

In Fig. 4 I have shown the three-wire branch bars $a^2 b^2 c^2$ as connected at one end to the bars $a b c$ and slab foundation A, the bars a^2 and b^2 being each a strip of sheet metal without joints, and the bar a^2 being arched to extend over and above the bars b and c , and the bar b^2 being arched to extend over the bar c , the bar c^2 being straight. The other ends of these bars are secured to said foundation by screws 12, similar to the screws 8, and the safety-fuses l' extending from said screws to the screws 11 of the auxiliary plates r and secured to the slab foundation thereby, and these plates r have connectors r' to receive the wires of the three-wire branch extending at right angles to the bars $a b c$. This construction provides for diverting the direction of the wires of the system and is applicable to a system composed of any number of wires.

While I have only shown and described a small distribution-board, it is obvious that the same arrangement may be extended to a board of any desired size.

My improved arrangement simplifies the construction, lessens the expense, and reduces the number of parts, and consequently the time consumed for construction, and the appearance of the board is enhanced.

I claim as my invention—

1. In a distribution-board for electric circuits, the combination with the parallel main-circuit bars, of branch-circuit bars composed of flexible comparatively thin strips of metal each passing beneath and connected at one point to one of the main-circuit bars and arched upward by bending to extend above

and cross over the adjacent main-circuit bar, and connections therefor directly to the foundation of the board, and electric connections therefrom to the main and branch circuit wires, substantially as specified.

2. The combination with the insulating slab foundation, of the parallel main-circuit bars a, b, c , the branch-circuit bars d, e , upon the slab foundation and the screws 7 for securing the same and the main-circuit bars a and c together and to the foundation, the branch-circuit bars f , upon the slab foundation, the screws 6 for securing the same and the main-circuit bar b together and to the foundation, said bars f being arched at each side of the bar b to extend above and cross over the bars a and c , the screws 8 passing through the foundation and securing the free ends of the bars d, e , and f to the foundation, and means for making electric contact with the main and branch circuit wires, substantially as set forth.

3. In a distribution-board for electric circuits, the combination with the parallel main-circuit bars, of branch-circuit bars composed of flexible comparatively thin strips of metal each passing beneath and connected at one point to one of the main-circuit bars and arched upward by bending to extend above and cross over the adjacent main-circuit bar, and connections therefor directly to the foundation of the board, and arched circuit-bars $a^2 b^2$ from the main-circuit bars for changing the direction of the main current, and electric connections therefrom to the main and branch circuit wires, substantially as specified.

4. The combination with the insulating slab foundation, of the parallel main-circuit bars a, b, c , the branch-circuit bars d, e , upon the slab foundation and the screws 7 for securing the same and the main-circuit bars a and c together and to the foundation, the branch-circuit bars f , upon the slab foundation, the screws 6 for securing the same and the main-circuit bar b together and to the foundation, said bars f being arched at each side of the bar b to extend above and cross over the bars a and c , the screws 8 passing through the foundation and securing the free ends of the bars d, e , and f , to the foundation, the terminal plates m , screws 9 for securing the same to the slab foundation and the fuses k, l , substantially as set forth.

Signed by me this 11th day of November, A. D. 1896.

HAROLD W. SHIONNARD.
